(57) **CLAIM**

The ornamental design for an ATM shield, as shown and described.

DESCRIPTION

FIG. 1 is a perspective view of an ATM shield showing my new design, shown in a used condition over a screen of an ATM machine shown in broken lines;

FIG. 2 is an enlarged portion view of the encircled portion labeled FIG. 2 in FIG. 1;

FIG. 3 is a front elevational view of FIG. 1;

FIG. 4 is an enlarged portion view of an encircled portion labeled FIG. 4 in FIG. 3;

FIG. 5 is a left side elevational view of FIG. 1;

FIG. 6 is a right side elevational view of FIG. 1;

FIG. 7 is a rear elevational view of the shield shown in FIG. 1, with the broken line environment of an ATM machine not shown for ease of illustration;

FIG. 8 is a bottom plan view of FIG. 7;

FIG. 9 is a top plan view of FIG. 1; and,

FIG. 10 is an enlarged portion view of encircled portion labeled FIG. 10 in FIG. 9.

The dot-dashed broken lines shown in FIGS. 1-4, 9 and 10 illustrate the boundary lines of the enlarged portion views of FIGS. 2, 4, and 10 and form no part of the claimed design. The even dashed broken lines shown in the drawings represent portions of the ATM shield that form no part of the claimed design.
